[57] **CLAIM**

The ornamental design for a portion of a bottle, as shown and described.

DESCRIPTION

FIG. 1 is a top perspective view of a portion of a bottle showing our new design;

FIG. 2 is a side elevational view of the portion of a bottle of FIG. 1;

FIG. 3 is a side elevational view of the portion of a bottle of FIG. 1 showing the side opposite that shown in FIG. 2;

FIG. 4 is a side elevational view of the portion of a bottle of FIG. 1 displaced substantially ninety degrees from FIG. 2;

FIG. 5 is a side elevational view of the portion of a bottle of FIG. 1 showing the side opposite that shown in FIG. 4;

FIG. 6 is a top plan view of the portion of a bottle of FIG. 1;

FIG. 7 is a top perspective view of the portion of a bottle of FIG. 1 showing the side opposite that shown in FIG. 1;

FIG. 8 is a top perspective view of a portion of a bottle showing a second embodiment of our new design;

FIG. 9 is a side elevational view of the portion of a bottle of FIG. 8;

FIG. 10 is a side elevational view of the portion of a bottle of FIG. 8 showing the side opposite that shown in FIG. 9;

FIG. 11 is a side elevational view of the portion of a bottle of FIG. 8 displaced substantially ninety degrees from FIG. 9;

FIG. 12 is a side elevational view of the portion of a bottle of FIG. 8 showing the side opposite that shown in FIG. 11;

FIG. 13 is a top plan view of the portion of a bottle of FIG. 8; and,

FIG. 14 is a top perspective view of the portion of a bottle of FIG. 8 showing the side opposite that shown in FIG. 8. The broken line showing of the remainder of the bottle in FIGS. 1-14 is for illustrative purposes only and forms no part of the claimed design.
